ATTORNEY

UNITED STATES PATENT OFFICE.

HENRY BAETZ, OF ST. LOUIS, MISSOURI.

HEATING ELEMENT.

Application filed April 3, 1926. Serial No. 99,567.

My invention has relation to improvements in heating elements or radiators and consists in the novel features of construction more fully set forth in the specification and pointed out in the claims.

The object of the invention is to provide a radiator in the form of a steam drum or casing having accordion plaited side walls, said casing being formed of thin sheet metal to provide great heat conductivity and lightness, the casing being surrounded by a suitable reinforcing frame to give the same strength and rigidity. The advantage of providing the plait is a great increase in radiating surface within comparatively narrow limits and the advantage of constructing the element of sheet metal is that the cost of manufacture may be kept down in addition to insuring high conductivity and lightness as above stated. Further advantages are better apparent from a detailed description of the invention in connection with the accompanying drawings, in which—

Fig. 1 is a side elevation of my improved radiator; Fig. 2 is an end elevation thereof; and Fig. 3 is a vertical cross section taken on the line 3—3 of Fig. 1; and Fig. 4 is an enlarged sectional detail of a fragment of the casing showing the seam.

Referring to the drawings, 1 represents a sheet metal drum or casing, the side walls of which are plaited as shown at 2, 2 the top and bottom walls 3, 3 preferably being plain surfaces. In the manufacture of the radiator, the ends of the sheet metal casing 1 are surrounded by and are cast within terminal members 4, 4 which themselves consist of castings. Each of said terminal members has cast onto its outer surface an enlargement 5 provided with a passageway 6 communicating with a pair of ports 8, 8 in the inner wall *a* of each member 4, said ports leading from the interior of the casing 1. A threaded nipple 7 is cast into the outer end of each enlargement 5. In the operation of the radiator, one of said ported enlargements 5 serves as a steam inlet while the other will serve as an outlet for spent steam and water of condensation. In order that steam under considerable pressure may be confined within the casing 1, the top and bottom walls of the casing are each reinforced and rendered rigid by a frame comprising bars of T iron 9 extending the length of

the walls 3, said walls resting against the T-bar. A rectangular frame of strap iron 10 is composed of side members 11, 11 extending transversely and in contacting relation with the plait 2, 2 and top and bottom members 12, 12 which are notched to receive the shank of the T 9. The number and spacing of the frames 10 is, of course, dependent on the length of the radiator and the steam pressure that it is desired to confine therein. It will be observed that the nipples 7, 7 are threaded to connect the radiator in the steam line so that it is a comparatively simple manner to connect the same for service, no special fittings being required. The edges of the metallic sheet forming the casing 10 are preferably joined by a seam 13 as shown in Fig. 4. The resulting unitary element that is thus provided is of great advantage as it makes for both simplicity, strength and durability.

Having described my invention, I claim:

1. A heating element comprising a sheet metal casing having plaited side walls, suitable terminal members cast over the extremities of said casing, one of said terminals being provided with an inlet and the other with an outlet, a stiffening member extending longitudinally of the top and bottom walls of said casing, and a reinforcing frame enveloping the casing, said frame having contacting relation with the plaited walls and with the stiffening members.

2. A heating element comprising a casing having its side walls plaited and its top and bottom walls plain, the extremities of said casing being cast into suitable terminal members, each of said members having a ported enlargement on its outer surface, one of which serves as an inlet and the other as an outlet and each of said ports having openings connecting the inlet and the outlet with the interior of the casing, a nipple cast into the outer extremity of each enlargement, and a suitable reinforcing frame enveloping the casing.

3. A heating element comprising a sheet metal casing having plaited side walls, suitable terminal members disposed over the extremities of said casing, one of said terminals being provided with an inlet and the other with an outlet, a stiffening member extending longitudinally of the top and bottom walls of said casing, and a reinforcing frame

enveloping the casing, said frame having contacting relation with the plaited walls and with the stiffening members.

4. A heating element comprising a sheet metal casing having plaited side walls, suitable terminal members on the extremities of said casing, one of said members being

provided with a passageway for the introduction of a fluent medium, and a plurality of lateral reinforcing frames enveloping ¹⁹ said heating element in spaced relation.

In testimony whereof I hereunto affix my signature.

HENRY BAETZ.
